UNITED STATES PATENT OFFICE.

BERRYMAN S. ALLEN, OF HURRICANE SWITCH STATION, ASSIGNOR TO
JOHN T. ALLEN, OF PULASKI, TENNESSEE.

COTTON-CHOPPER.

SPECIFICATION forming part of Letters Patent No. 234,219, dated November 9, 1880.

Application filed June 15, 1880. (No model.)

To all whom it may concern:

Be it known that I, BERRYMAN S. ALLEN, of Hurricane Switch Station, in the county of Maury and State of Tennessee, have invented 5 certain new and useful Improvements in Cotton-Choppers; and I do hereby declare the following to be a full, clear, and exact description of the same, reference being had to the accompanying drawings, forming part of this 10 specification, in which—

Figure 1 represents a longitudinal sectional view of the machine arranged as a planter. Fig. 2 is a similar view of the machine arranged as a chopper and cultivator. Fig. 3 is 15 a plan view of Fig. 2. Fig. 4 is a cross-sectional view taken on the line xx , Fig. 2. Fig. 5 is a detailed view of the drill; Fig. 6, a detached view of the seed-dropper, and Fig. 7 a detail view of the coverer.

20 Similar letters of reference in the several figures denote the same parts.

This invention relates to that class of machines employed in the cultivation of cotton which combine planting, plowing, and chopping; and it consists, first, in certain improvements in the main frame; and, secondly, in certain improvements in the chopping devices, all which I will now proceed to describe.

In the drawings, A represents the main 30 frame of the machine, consisting of two long parallel inner timbers, $a a$, and two short outer timbers, $a' a'$, the long timbers being united at their forward ends by a cross-bolt, b^2 , which also serves to secure the draft-pole P. Permanently secured to this main frame are three 35 sets of standards, $a^2 a^2$, $a^3 a^3$, $a^4 a^4$, and $a^5 a^5$. The standards $a^2 a^2$ and $a^4 a^4$ are provided with a series of transverse holes or perforations, $c c$, and to them are attached the guiding-handles C C by means of a bolt, c' , passing through said holes. By changing the bolts to different holes in the series the handles 40 may be adjusted higher or lower, as desired.

B is a secondary frame, consisting of longitudinal parallel timbers $b b b b$ and a cross-timber, b' . The timbers b are slotted or mortised at their forward ends to admit of their being fitted over the standards, a^3 of the main frame, and transverse bolts b^2 are em-

ployed to secure them to said standards. The 50 timbers b are further provided with shoulders or tenons on their rear ends, which enter corresponding mortises in the cross-timber b' . A stout rod or bolt, D, passes through one or the other of the series of transverse holes in the 55 standards a^2 , and serves as means for holding the frame A in any desired relation to the secondary frame, as will be presently explained. The secondary frame B forms the bearing for a revolving shaft, E, to which the seed-dropping arms or stirrers e are connected when the machine is used as a planter, as shown in Fig. 1, or constitutes the bearings for a similar revolving shaft, E', when the machine is 60 used as a chopper and cultivator, as shown in Fig. 2.

F are the transporting or driving wheels, adapted to be secured to the ends of either the shaft E or the shaft E', according as the one or the other is used, so as to rotate the 70 shaft when the machine is moved forward.

The construction of the secondary frame is such that it can be readily taken apart to admit of the application of either the shaft E or shaft E'.

G is the harrow, consisting of two diagonal timbers, $g g$, mortised into the longitudinal timbers $a a$ of the main frame with their mitered ends abutted together, as shown in Fig. 3, and provided with teeth $g^1 g^2 g^3$, increasing 80 in length from the central teeth outward.

The teeth g^2 not only pass through the timbers $g g$ but also through the timbers $a a$, and serve as means for firmly connecting the parts together.

The upper ends of the teeth are screw-threaded and provided with nuts g^4 .

Metal bearing-plates g^5 may be interposed between the nuts and the top face of the timbers g if deemed necessary or desirable.

When the machine is arranged for planting the shaft E, with the hopper H mounted thereon, is applied to the secondary frame B, and the wheels secured to the end of the shaft, as shown in Fig. 1. The shaft is provided with 95 seed-dropping arms or stirrers e within the hopper, as before described.

Behind the harrow and in front of the hop-

per a drill-tooth, I, is arranged. This tooth has a downwardly-curved point, and is welded or otherwise connected to a shank, i, that passes up through a block, I', as shown. A heel-projection, i', is provided at the rear of the tooth, for the purpose of widening and clearing the furrow made by the point of the tooth and to better prepare such furrow for the reception of the seed.

10 The heel may be made a part of the tooth itself; but is preferably secured to a shank, i², which passes up through a perforation in the rear part of the tooth, and also through the block I'.

15 The shanks of both tooth and heel are capable of adjustment up and down in the block I', for the purpose of causing a furrow more or less deep to be made.

The block I' is made to fit in between the 20 long parallel timbers a a of the main frame, and is held by means of a cross-bolt, J, passed through said timbers and through its forward end. A metal strap, i³, passes over and is secured to the top and sides of the block, and 25 projects laterally under the timbers a a, to limit the upward movement of the rear end of the block and assist in holding the drill to its work.

The timbers a a at their rear extremities are provided with extensions K K, connected by 30 bolts k k, and adapted to be swung laterally toward and from each other, as shown in Fig. 3. These extensions are slotted vertically near their outer ends for the reception of the standards l l of a coverer, L, and their proper relation is preserved by means of a plate, M, having segmental slots m m, and bolts m', and clamping-nuts m².

In the operation of the machine thus organized the teeth of the double harrow run on 40 both sides of the ridge and pulverize and properly prepare the ground. The drill then opens the furrow for the reception of the seed dropped from the hopper by the rotation of the stirrers therein, after which the coverer operates to 45 cover the open furrow and complete the planting.

When it becomes necessary to work the cotton the first time after it comes up the wheels of the machine are taken off and the shaft E 50 and hopper removed from the secondary frame, and the shaft E', carrying the trundle-head E², substituted in their stead. The block I, carrying the drill-tooth, is then removed, and in its place is secured a standard, N, by means 55 of the same cross-bolt J. This standard N forms the fulcrum and support of a lever, O, which is connected at its forward end to a vertically-moving frame, P', and receives motion from the trundle-head E², at its rear end.

60 The frame P' is made in two parts, p p', and is rendered adjustable by means of slots p² in its upper part and projections p³ on the lower part entering said slots, and is held in adjusted position by clamping-screws and bolts 65 p⁴. The lower part, p', slides in vertical grooves or ways on the inner faces of the timbers a a,

and carries at its lower end a cutting knife or blade, R. In the downward stroke of the frame the lower end of the part p comes in contact with the top of the timbers a a, and thus limits the movement of the frame. By adjusting the parts of the frame on each other it is evident that the depth to which the knife enters the ground can be regulated at pleasure.

The trundle-head consists of two plates, E², 75 rigidly secured to a continuous shaft, or, as shown, to the proximate ends of a divided shaft, and united by means of cross-bars e' and nuts e². The ends of the cross-bars are screw-threaded, and pass through radial slots 80 e in the plates, as shown. These cross-bars are adapted to engage with the rear end, o, of the rock-lever O, which operates the chopping-knife frame, and by adjusting them in or out in the slots they can be made to engage more 85 or less frequently with the lever, and thus regulate the length of time the knife is depressed and kept in active cutting operation. The pivot of the lever O is adapted to be adjusted up or down the standard to correspond 90 to the adjustment of the cross-bars in the trundle-head.

As a further change of organization, the coverer L is removed and cultivators T substituted in its stead. Thus arranged the machine operates to chop out the cotton at regular intervals and to plow both sides of each row at once.

The cultivator-plows can be adjusted nearer to or farther from the rows by changing the 100 position of the adjustable extensions, and they can also be made to enter more or less deeply into the earth by changing the position of the cross-bolt D, which controls the adjustment of the main frame.

From the foregoing it will be seen that by my 105 invention I am enabled to accomplish both the planting and subsequent cultivation of cotton by a single machine and a few simple attachments.

Although I have described herein the construction and operation of all the parts of the machine,

I only claim as my invention and desire to 110 secure by Letters Patent—

1. In a cotton-stalk chopper, the combination of the secondary frame, supported by the shaft and wheels, as set forth, the main frame, hung to the secondary frame at b², the adjusting-standards a³, and the cross-bolt D, substantially as described.

2. In a cotton-stalk chopper, the combination, with the main frame A, having the standards a² a³, of the secondary frame consisting of the longitudinal timbers b b and cross-timber b', and adapted to receive and accommodate the trundle-head shaft, substantially as described.

3. In a cotton-stalk chopper, the trundle-head consisting of the two plates provided 125 with radial slots, and having the adjustable cross-bars, substantially as described.

4. In a cotton-stalk chopper, the combination of the knife-frame, the rock-lever, and the trundle-head having the radially-adjustable cross-bars, substantially as described.

5. In a cotton-stalk chopper, the combination of the trundle-head having the radially-adjustable cross-bars, and the rock-lever hav-

ing the adjustable pivot, substantially as described.
